UNITED STATES PATENT OFFICE.

GLENN D. BOTHWELL, OF SPRINGPORT, MICHIGAN, ASSIGNOR OF ONE-THIRD TO GUY J. BOTHWELL, OF LONDON, ONTARIO, CANADA.

BRIDGE FOR DIAPHRAGM VIOLINS.

Application filed February 26, 1923. Serial No. 621,270.

To all whom it may concern:

Be it known that I, GLENN D. BOTHWELL, a citizen of the United States, residing at Springport, in the county of Jackson and 5 State of Michigan, have invented a new and useful Bridge for Diaphragm Violins, of which the following is a specification.

This invention relates to stringed musical instruments and particularly relates to 10 string supporting bridges for such instruments.

It is the object of the invention to provide a string-supporting bridge adapted to freely respond to the vibrations of the supported 15 strings and to provide supporting means for said bridge adapted to transmit such vibrations to the diaphragm element of the shell or sound-box of the instrument across which the strings are extended.

20 In attaining this object, the invention contemplates employing an intermediately pivoted lever, one extremity of which is adapted to support the string-bridge while the other extremity of said lever is connected 25 to the diaphragm element of a sound-box, preferably centrally of said element, said bridge being adapted to pivotally vibrate about its other end to actuate said lever and transmit vibratory movement to said dia- 30 phragm element.

A preferred embodiment of the invention is hereinafter described, and is illustrated in the accompanying drawing, wherein,

Fig. 1 is a view in side elevation of a 35 stringed instrument improved in accordance with the invention.

Fig. 2 is a longitudinal sectional view of the same.

Fig. 3 is a transverse sectional view, taken 40 on line 3—3 of Fig. 2.

In these views, the reference character 1 designates the strings of a musical instrument and 2 the body shell or sound-box across which said strings are extended. Said 45 sound-box comprises a bottom board 3, the top face of which is routed out to form a cavity of suitable proportions to serve as the sound-box chamber, and 4 is a top-board marginally secured to the board 3 and suffi- 50 ciently thin to serve as a diaphragm for the sound-box. 5 is a substantially rigid bridge member which transversely spans the sound- 55 box seating upon opposite margins of the same. The string-supporting bridge 6 centrally surmounts the bridge 5, the ends of

the former respectively engaging a vertical flexible post 7 and a lever 8 mounted upon the latter. Said post is rigidly anchored at the lower end in a groove 9 in the bridge 5, and the bridge 6 is formed in its lower edge 60 with a V-shaped notch engaging said post. The lever 8 passes freely through a slot 10 in the bridge 5 and has its lower end rigidly secured to the diaphragm 4, preferably at the center of the latter, by a screw 8'. The upper end of said lever is pointed as indicated at 11 and seats in a V-shaped notch in the corresponding end of the bridge 6. Below the point 11, and within the slot 10, the lever 8 is pivoted upon a pin 12 mounted transversely in the bridge 5. The lever 8 is laterally bent, just above the pivot pin 12, to establish the desired off-set relation of the point 11 and pin 12 with relation to the central point of the diaphragm 4, which is the 70 point of attachment of the lever, the intermediate portion of the lever being reduced in thickness to render it flexible. By virtue of this off-set relation, vibratory pivotal movement of the lever upon said pin is applied to the diaphragm at an acute angle to the plane thereof. This motion is resolved into components respectively transverse to and parallel with the diaphragm, the former acting to vibrate the diaphragm and the latter be- 75

ing absorbed by flexing of the intermediate portion of said lever. The sound vibrations of the air within the sound-box are adapted to be emitted through a central opening 13 in the member 3, which opening is in communication with the restricted end of a horn 14 through a passage 15, these features how- 80 ever being more especially the subject-matter of my copending application filed Feb. 26, 1923, Serial Number 621272. 85

When one or more of the strings 1 are set in vibration, by application of a bow or by other means for agitating said strings, the resulting vibrations are directly communicated to the bridge 6, which has a limited 100 freedom of movement for response to such vibration. The vibrating of the bridge 6 has the nature of a bodily lateral movement, the post 7 flexing to permit such movement. The upper end of the lever 8, owing to its 105 engagement in the notch of the bridge 6, is moved laterally in unison with the bridge, thus causing a pivotal vibration of said lever upon the pin 12 as a fulcrum member. Flexure of the lower portion of the lever acts 110

2
to absorb the component of the lever vibration parallel to the diaphragm, so that the diaphragm vibrates responsively to the component of the lever movement transverse to the diaphragm. The resulting air vibrations within the sound-box are emitted through the opening 13, passage 15, and horn 14.

The effect of transmitting the vibrations 10 of the strings to the diaphragm of the sound-box by a lever or equivalent solid element is to considerably intensify the emitted sound vibrations as compared to an instrument in which the air is required to transmit the vibrations of the strings to the sound-box.

What I claim is:—

1. In a stringed instrument, a sound-box having a diaphragm, strings extending across said sound-box, a bridge supporting said strings adjacent said diaphragm, a flexible support for one end of said bridge, per-

mitting vibratory movement of the latter, and a support for the opposite end of said bridge pivotal about an axis substantially parallel to the strings and engaged with said diaphragm to impart to the latter the vibrations of said bridge. 25

2. In a stringed instrument, a sound-box having a diaphragm, strings extending across said sound-box, a stationary bridge spanning said diaphragm, a vibratory bridge supporting said strings, a flexible support interposed between said stationary and vibratory bridges, and a vibratory lever pivotally interposed between said stationary and vibratory bridges and fixedly engaged with said diaphragm to subject the latter to the vibrations of said vibratory bridge. 30 35

In testimony whereof I sign this specification:

GLENN D. BOTHWELL.
